MACHINE FOR MAKING ENVELOPES

Filed Dec. 5, 1927

FIG. 3.

INVENTOR:
FREDERICK J. PARKS
BY
George W. Saywell
ATTORNEY.

UNITED STATES PATENT OFFICE.

FREDERICK JAMES PARKS, OF CLEVELAND, OHIO, ASSIGNOR OF ONE-HALF TO SHERMAN W. SCOFIELD, OF CLEVELAND, OHIO.

MACHINE FOR MAKING ENVELOPES.

Original application filed May 10, 1924, Serial No. 712,200. Divided and this application filed December 5, 1927. Serial No. 237,717.

The subject matter of this application is divided out of my pending application Serial No. 712,200, filed May 10, 1924, upon machines for making envelopes.

5 This invention particularly relates to new and improved means for scoring and gumming envelope blanks, whereby the scoring is effected in advance of the gumming so as to obviate the fouling of the scoring mechanism by the gum; and to a new and improved form 10 of curling or turning knife for insuring the folding of the lateral side flaps of the envelope blank down upon the blank body. Other detailed improvements will be herein- 15 after fully described and are fully shown in the accompanying drawing. Certain features shown in the accompanying drawing and also hereinafter referred to relate to means for gumming the side flaps and the side 20 tabs of the envelope blank whereby the same are secured to the blank body to form the envelope side closures, and means for controlling the operation of said gumming means, but these gumming features of the machine are 25 claimed in said pending application Ser. No. 712,200, from which the subject matter of this application is divided out, and the claims of this application are limited to the envelope 30 machine and the new and improved turning knife.

The annexed drawing and the following description set forth in detail certain means embodying my invention, such means constituting, however, but one of the various forms 35 in which the principle of the invention may be applied.

In said annexed drawing:

40 Figure 1 is a fragmentary plan section of an envelope machine embodying my improvements, the section being taken in the plane represented by the line 1—1, Figure 2;

Figure 2 is a longitudinal vertical section, taken in the plane indicated by the line 2—2, Figure 1;

45 Figures 3, 4, 5 and 6, are fragmentary transverse vertical sections, upon an enlarged scale, taken, respectively, in the planes indicated by the lines 3—3, 4—4, 5—5, and 6—6, Figure 1;

50 Figure 7 represents a plan view of the envelope blank as it emerges from the folding device preparatory to being fed into the im-

proved side sealing devices described, shown and claimed herein; and

Figure 8 represents a plan view of the completely folded and gummed envelope as it passes from the devices forming the subject matter of this application.

Referring to the annexed drawing, in which the several elements are indicated by the same respective ordinals in the different views, I indicate by the ordinal 2, Figure 7, an envelope blank at a certain stage of its conversion into a complete envelope, herein-after fully described, which has been folded so as to have a mouth closure flap detachably interlocked with an adjacent pocket, as fully shown and described in my U. S. Patents Nos. 1,316,737, and 1,580,441. The improvements of this application relate only to features of 70 an envelope machine adapted to complete the operations upon the blank 2, Figure 7, all as will now be described in detail, having reference to the accompanying drawing.

The envelope blank 2, in the form shown in Figure 7, but lacking the gum strips 34, Figures 4, 5 and 6, emerges from the transverse folders (not shown in this application but shown, described and claimed in said Patents Nos. 1,316,737 and 1,580,441) and is fed into 80 the guide 16, Figures 1 and 2, whence it is conducted into the bight of the upper and lower peripherally engaging rolls 17 and 18 whence emerging from which it is received upon the plate 19 over which it passes to certain scoring, gumming and side sealing devices which will now be described in detail.

The envelope blank 2, Figure 7, is fed over the plate 19 into certain scoring rolls 35 and 36, of which there are two pairs, the lower 90 rolls 36 being formed with end flanges 36', Figure 3, against which the outer end-face portions of the rolls 35 closely register to define the lateral edge flaps 32, plainly shown in Figure 7. The end faces of the upper rolls 95 35 prevent the turning in of the side flaps 32 further than the position shown in Figure 3 until said side flaps 32 intersect the bevel faces 40 of portions 39³ of a pair of turning knives 39, Figures 4, 5 and 6, which progressively fold down the side flaps 32 until they are finally sealed down upon the envelope portions 29 and the glue 34 to produce the complete envelope 8 shown in Figure 8. During

these operations the envelope is conveyed by upper rolls 21, 41, 43 and 45, and respectively cooperating lower rolls 22, 42, 44 and 46, over the plate 47 and passes therefrom to further 5 rolls and a stacking device, not forming part of this invention, and one specific form of which is plainly shown, described and claimed in said U. S. Patent No. 1,580,441.

During its passage from the scoring rolls 10 35 and 36 to the turning knife 39, the portions of the blank 2 designated by the ordinal 29 are supplied with glue 34 by certain devices shown, described and claimed in said application Serial No. 712,200, from which the subject matter of this application is divided out. 15 Briefly, this gumming operation is effected by the following means. Suitably mounted in the frame 1 of the machine is a solenoid 88 having a core 87 to the upper end of which is 20 pivotally secured the free end of a lever 86 whose other end is secured to a transverse shaft 89 rotatably mounted in the frame 1. Also secured to the shaft 89 and adjacent the two respective ends thereof, are two arms 90, 25 of which the arm on one side only of the frame is shown in the accompanying drawing, these arms 90 having U-shaped outer ends between the members of which are mounted rollers, of which one roller 91 is plainly shown in Figure 2. A pair of vertically-reciprocable columns 92, one of which is shown, suitably guided by brackets, of which one, 93, is shown in Figure 2, and guided by frame bosses 102, are supported by the rollers 91.

30 One boss 102 appears in Figure 2. These columns 92 support in brackets at their upper ends a transverse tubular shaft 84. Adjustably secured in brackets 104 supported by said transverse shaft 84 are a pair of pending tubular supports 26 for gumming devices 25. These supports 26 communicate intermediate their upper and lower ends with tubular sections 26' connected by means of flexible tubes 27 with tubular elbow-sections 45 26' which in turn receive suitable glue or other gumming material from a source of supply (not shown) through conduits 27' of which fragmentary portions are shown in Figure 2. A flat spring plate 85 suitably supported in the frame 1 is formed at one edge 50 into downwardly extending fingers or trips 23 and 24. The ends of these fingers 23 and 24 are adjacent the upper edge of a plate 55 over which the envelope blank 2 travels after 55 emerging from the scoring rolls 35 and 36, and after traversing an intermediate metal bar or plate 20 hereinafter more fully described. The lower ends of these trips 23 and 24 which contact with the plate 55 are longitudinally spaced, as plainly shown in Figures 1 and 2, for a purpose hereinafter fully described. Mounted upon the intermediate plate 20 and electrically insulated therefrom is a transverse metal bar 75, Figure 1, upon 60 65 which the spring plate 85 is mounted and se-

cured by means of nuts 60, one of which forms a binding post to which an electric wire 80 is secured. The wire 80 leads to a battery (not herein shown) and a second wire (not shown) connects this battery and the solenoid 88. A third wire (not shown) connects the solenoid 88 with a binding post (not shown) electrically connected with the plate 55. The frame of the machine is insulated from the metallic elements forming the electric circuit which has just been described.

70 From the foregoing description and the accompanying drawing, it will be evident that when the circuit is completed and the coil 88 is energized, the core 87 being drawn 75 into the coil 88 will rock the shaft 89 so as to cause the arms 90 to lift the columns 92 and consequently the transverse shaft 84 and the brackets 104, whereby the supports 26 and the gumming devices 25 will be raised into 80 the position plainly shown in Figure 2. This is the normal position of the gumming devices 25 and in this position these devices do not feed gum. When the coil 88 is deenergized, the gumming devices 25 fall by their own 85 weight and cause gumming rollers 65 to contact with the surfaces 29 of the envelope blank 2, and properly supply and spread the gum in the manner fully described in said pending application Serial No. 712,200. The 90 opening and closing of the electric circuit is controlled through the medium of the spring fingers or trips 23 and 24. The lower ends of these fingers 23 and 24 lie in the path of the envelope blank 2 in such a manner that 95 said blank passes under said lower ends and raises the spring trips 23 and 24 to break the circuit. This results in the deenergizing of the coil 88 and the consequent release of the columns 92 which are lowered under the force 100 of gravity and which consequently lower the gumming devices 25, and allow gum to escape from the gum nozzles as soon as the rollers 65 encounter the envelope blank. The 105 gumming devices 25 are so disposed that the 110 gum from the nozzles is deposited upon the longitudinally arranged portions 29 of the envelope 2 adjacent the portions thereof which have been previously scored by the 115 rolls 35 and 36. The mechanism shown is so 120 arranged that these portions 29 are parts of the blank body but, of course, it is entirely within the range of the invention to deposit the glue 34 upon the side flaps 32. This 125 deposit of the glue 34 does not occur until the forward edge of the envelope has passed beneath both of the fingers 23 and 24. It is evident that until such action has taken place, the electric circuit will not be broken. The 130 arrangement is such that by the time the circuit is thus broken a portion of the envelope blank has passed forwardly of the gumming devices 25 and consequently the gum is deposited upon the portions 29 beginning at a 135 point somewhat removed from the forward

edge of the blank 2. Also, it is evident that the circuit will be again closed just as soon as the rear edge of the blank 2 passes from beneath the rear trip 23. The arrangement is such that the consequent stopping of the discharge of the gum takes place upon a portion of the blank 2 somewhat removed from the rear edge of said blank.

It is particularly pointed out that I have positioned the scoring rolls 35 and 36 forwardly of the gumming devices 25. This is an extremely important improvement in that I thereby obviate fouling the scoring devices with the gum, which is what happens, and with a very great annoyance and loss of efficiency, when the scoring of the blank is effected subsequent to the gumming, because, of course, the gum lies open and is exposed during the scoring operation since the scoring must be effected before the side enclosures 32 are folded over.

Referring particularly to Figures 3, 4, 5 and 6, I have devised a new construction of a folding knife which obviates inconvenience and delay caused by excessive fouling of the machine by gum. This is a two-part folding knife 39—39². When the beveled curling face 40 is formed upon the body of the knife 39, the gum 34 will accumulate thereunder and cannot readily be completely removed. So I have spaced the portion 39³ of the knife from the body portion 39 thereof, as plainly shown in Figures 1, 4, 5 and 6, connecting the same by straps 37, so that through the medium of the opening 38 the gum can be readily and conveniently wiped off the knife 39—39². These knives 39 are secured by means of bolts 63, Figure 1, to the frame 1, the longitudinal alignment of the knives being assured by means of straps 39' secured to aligning members 39², the bolts 63 intersecting said straps 39'. By means of two series of transversely aligned holes 62 in the frame 1, the knives 39 can be adjusted for envelopes of varying widths. Other parts of the ma-

chine are adjustable for different size envelopes; for instance, the scoring rolls 35 can be transversely adjusted upon the shaft 48 to which they are secured by the key-way 48', a suitable size intermediate spacing roll 50 being substituted, these spacing rolls 50, as plainly shown and described in said U. S. Patent No. 1,580,441, being resiliently confined between the pair of rolls 35 to allow for the accommodation of the thickness of the envelope 2 between the roll 35 and the flange 36' of the roll 36, Figure 3. The scoring rolls 36 are adjustably secured to a transverse shaft 49. The gumming devices 25 can be transversely adjusted upon the support 84. In order to accommodate the envelopes when passing between any of the cooperating parts of the rolls, the shafts to which the latter are secured are resiliently mounted in the frame 1 in yielding bearings pressed downwardly by means of springs whose tension is adjusted by screws 53, the desired adjustment being fixed by means of lock nuts 54, Figure 2.

Cooperative driving mechanism for actuating the feeding rolls, scoring rolls, etc., are provided (not shown in detail in this application, but well known in various forms to those skilled in this art).

What I claim is:

1. In means for turning down side flaps of strips upon the body portion thereof, a turning knife having an outer body portion and an inner portion spaced from said outer portion and formed with an inner beveled progressive turning edge.

2. In means for turning down side flaps of strips upon the body portion thereof, a turning knife having an outer body portion and an inner portion progressively spaced therefrom so as to form an acute angle therebetween, said inner portion being formed with an inner beveled progressive turning edge.

Signed by me this 2nd day of December, 1927.

FREDERICK JAMES PARKS.
